US00D657772S

(12) **United States Design Patent**
Shadovitz et al.

(10) **Patent No.:** **US D657,772 S**
(45) **Date of Patent:** **** Apr. 17, 2012**

(54) **TELEPHONE BASE UNIT**

(75) Inventors: **Michael Shadovitz**, Fukuoka (JP);
Takashi Hasegawa, Fukuoka (JP);
Toshiya Moriyama, Fukuoka (JP)

(73) Assignee: **Panasonic Corporation**, Osaka (JP)

(**) Term: **14 Years**

(21) Appl. No.: **29/399,708**

(22) Filed: **Aug. 17, 2011**

(51) LOC (9) Cl. **14-03**

(52) U.S. Cl. **D14/150**

(57) **CLAIM**

We claim the ornamental design for a telephone base unit, as shown and described.

DESCRIPTION

FIG. 1 is a front perspective view of a telephone base unit of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The unevenly-segmented broken lines represent bounds of the claimed design. The evenly-segmented broken lines depict unclaimed environment. The broken lines form no part of the claimed design.

1 Claim, 7 Drawing Sheets
